LE VERT CLARK, OF DETROIT, MICHIGAN.

HEATING, VENTILATING, STREET-ANNUNCIATING, AND DRAFT-PRODUCING SYSTEM
FOR CARS.

1,051,687.

Specification of Letters Patent. Patented Jan. 28, 1913.

Application filed March 8, 1912. Serial No. 682,472.

To all whom it may concern:

Be it known that I, LE VERT CLARK, a citizen of the United States, residing at Detroit, in the county of Wayne, State of Michigan, have invented new and useful Improvements in Heating, Ventilating, Street-Annunciating, and Draft-Producing Systems for Cars: and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to combination sound transmitting, ventilating, and heating devices, for cars; particularly to the specific 20 means employed to stimulate the fire in an ordinary stove by a forced draft which may also be diverted to ventilate the car; likewise all its features may be used at the same time, or separately, that is to ventilate, 25 and heat the car and to use the pipe, through which to call the names of streets. I designate it as an acoustic ventilator and forced fire draft for cars. Whereby the car is constantly supplied with fresh warmed air, 30 in winter, and cooling breezes in summer; and at the same time the motorman may use the device as a street annunciator.

In the drawings: Figure 1 is a side view and vertical section along the dotted line 35 1—1 of Fig. 2. Fig. 2 is a lengthwise, approximately horizontal, or midway, sectional view, between the upper and lower sides of the main pipe; and top view below the roof.

A is a car partly broken away which may 40 have an end wall B separating it from the vestibule D which latter may be divided by a partition B' and have windows C closing in the vestibule from the outer air.

F is the end of the roof, over the vestibule. F' the higher roof portion, over the 45 end transoms J and side transoms J'.

10 is the air conveying pipe communicating at its receiving end with the outer fresh air through its intake 18. This pipe is bifurcated at 14 so that one branch communicates with a discharge end portion 12 opening inside the car; while the other branch 30 terminates in an air jet nozzle 34 pointing upward and located preferably somewhere

in the axial center of the smoke pipe H; 55 which latter communicates with the combustion chamber of a conventional stove X.

U is the smoke pipe damper.

Z' is the air inlet below the fire X' of the 60 stove.

Z is an air inlet in the warm air casing Y enveloping the stove and as much as possible of the smoke pipe H, or other heat engendering apparatus in lieu of a stove and smoke pipe.

V is a door closing the inlet Z to control the air from the car, going in the inlet Z.

G is the place of juncture of the casing Y and pipe 10, both having a combined opening 12 into the car through the transom J 70 or J'. Its action is something like that of a river that flows into the sea (12) from the confluences of two or more rivers (Y) and its tributary (45), (10) and (24); also having another smaller occasional outlet (30). 75 The side transom being used merely to leave the front transom for use of car street-signs. One transom will serve as well as another for like purposes. Or the combined pipes, (casing Y, 10, and 24) may empty into the 80 car at any other convenient place. Electric or other heat generating devices, not illustrated, may also be used inside the casing Y instead of the stove X with good results as regards the heat, ventilation and sound, 85 transmission features of my device. The casing may have a loose fitting door Y', hinged at V preferably not air-tight; through which to put the stove and give access to the inlets, fire doors and ash pit 90 of the stove. A jacketed pipe 45 below the car floor, or above as shown in dotted lines, having openings 45' inside the car, and joined to the casing Y, may serve as inlets, instead of Z, to draw away the air from top 95 of floor up through opening 12; so as to put it into more general circulation, throughout the interior of the car.

20 is a damper which may be opened and closed by the rod 35, movably connected at 100 23, in convenient reach of the motorman or by any other suitable means. The damper may be circular for a round pipe or rectangular and hinged at its edge 21, in the square pipe illustrated; where it is raised 105 and shut by an ordinary rod suitably connected such as is commonly used to open and close transoms over house-doors. The

damper is used to control the passage of air coming into pipe 10. Other suitable dampers and ways to operate them are not illustrated. The branch 30 may have another 5 valve or damper 20' to control the passage of air through it, and preferably located either close to the pipe 10 or at its juncture with the smoke pipe H. The branch 30 may also be divided into three sections, 31, 32, 10 and 33, put together by union joints 29 and 29. Section 31 may be left permanently in the car; and section 33 left permanently in the smoke pipe; when the lower portion of the smoke pipe H, together with the stove 15 X and its casing Y are all removed from the car in summer. They being made preferably removable for that purpose; by disconnecting at intersection with the roof F. The upper section H' of the smoke pipe and 20 all other pipes or branches, are preferably left permanently in the car. In regular open or summer cars the same system may preferably be installed, so as to get the benefit of the air currents in pipe 10 to convey sound received therein through the branch 24, when the stove X and smoke pipe H and the casing Y are usually dispensed with.

11 is the mouthpiece of the sound receiving branch, through which the motorman calls the names of streets into the ventilator pipe opening into the car as described.

24' is the telescopic extension, to raise and lower the mouthpiece, which may be 35 clamped at varying heights by the thumb-bolt 22.

It is preferable, when the draft is on, through the branch jet 34, that the hood O should then be raised to give freer passage 40 to smoke, and air through branch 30 and pipe H to the outer air. Which may be done in the ordinary way by pulling down the short end of a lever P hinged at Q to a bracket on the smoke pipe, and having the 45 hood attached to the lever. The hood O will be returned to its place when the draft is off, to keep out the rain in the usual way.

R is a rod that brings the operation of the hood in reach of the motorman.

50 S are radiator fins preferably of bright metal as a better heat radiating medium attached to the smoke pipe H inside the casing Y; which serve the double purpose of drawing the heat from the pipe H into the 55 surrounding air; and also act as baffles to prevent drawing out the air too rapidly, from inside the casing Y before it is sufficiently heated, under the strong drawing action of the parallel currents of cold air 60 coming into the car through pipe 10; and air entering pipe casing Y, through its feeder 45, and air going through the inlet Z, when the door Y is shut, into the casing pipe thence into pipe 10 and into the car at 65 12. The cold and hot air and sound there-

fore meet and mingle at G, like an atomizer works; thence may go into the car, under impetus of a rotary power driven fan N, in the pipe, which keeps the draft uniform and constant when the car is standing still, or if 70 the wind is adverse. At other times the motion of the car may usually be sufficient with favorable winds. The fan may be placed on the same axle shaft, and driven by an electric motor M, which I preferably place axially 75 coincident with the fan inside the pipe 10. But any driving means may be placed outside the pipe and suitably connected to the fan by a chain, belt, or otherwise, not illustrated. The fan, placed at either end of the 80 inside motor, as preferred, and the motor and their coacting parts may be placed on the same base W making a unit easily removable from the pipe 10.

In operation: The cold fresh air comes into 85 pipe 10 through its intake 18 either by motion of the car or from air blowing into the intake; or the fan enables the apparatus to furnish a steady air current regardless of the motion of the car or wind. If the 90 damper 20 is open (down) the air at once goes through the opening 12 into the car. The force or quantity of air being regulated and controlled by the dampers. If the car is divided into compartments not here illustrated but seen in my application Serial No. 536,082, the discharge end 12 of pipe 10 may be bifurcated, as described therein and not shown here. The action of the fresh air in pipe 10 after passing the junction G with 100 the casing pipe Y is to draw the warm air out of the casing as stated, which is greatly freshened thereby and both currents commingle and become modified in temperature; the air being rarefied, becomes a better sound 105 medium, as it is projected into the car, over the heads of the passengers. Which process is facilitated by opening wide the inlets 45' and Z, to the casing. The inlets having only the one function of admitting air from 110 the floor of the car. The presence of the stove X is to heat the air inside the casing Y. For which purpose the colder air of the car being nearer the floor, is drawn into the casing through the inlet Z, or around the 115 door Y', thereby promoting a general circulation of fresh tempered air throughout the full interior of the car. The action, of this new breathing apparatus for the car, is very much like that of a man; who standing 120 erect, with head up, throws back his shoulders and takes a deep inhalation of fresh air from the highest available strata in his reach; where the air is purer than the germ laden atmosphere closer to the ground where 125 unsanitary dust is stirred up by movement of the vehicle itself and rotation of the wheels, a fact obvious to most any observer. When the wind is in the same direction, a moving car, always on bad, single-rail, track, 130

carries along with it, a cloud of dust under the full length of the car; which dust and germs would enter the car to be breathed by passengers, if the air is drawn into the car 5 through holes near the ground or in the floor; which is the strange unwise provision of some of the so called good heating and ventilating systems and it will eventually be prohibited by the boards of health.

10 To start a fire in a mass of cold fuel is difficult; and to maintain a steady heat, afterward needs greater care and watchfulness, for at least an hour or more in cases where only the heat of the fire itself is to 15 be depended on to produce a natural draft. To create the necessary heat requires a strong draft, and the stove won't draw until the requisite heat creates the necessary draft. In consequence of this paradox there is considerable coaxing, vexation, and always delay in the matter of starting the fire and heating car stoves with necessarily short smoke pipes; it being understood that tall stacks are otherwise always necessary to 20 25 make strong natural draft in factory chimneys. All this trouble may be obviated and sufficient fire draft immediately started in the following manner: Close pipe 10 by raising one side of the damper 20 as indicated, by the dotted lines, and open the damper 20' in branch 30 which leaves a clear passage for air coming into the intake 18 to be deflected by damper 20 into branch 30 and forced through by the motion of the car or 30 35 by the rotary fan N, so as to go under sufficient impulsive action into the smoke pipe H, through the air jet nozzles 34, thence out through the top of pipe H'. This action creates a partial vacuum above the fire X' 40 which is filled by air coming in below the fire, through the inlet Z' in the stove; whereby sufficient air is drawn through the fire to stimulate it into great activity in a few minutes. The draft is regulated and controlled 45 by the dampers 20 and 20' as stated. For this reason a fire may remain dormant a part of the day and "banked," all night when not in use, to save fuel, yet keep the car comparatively warm. But with the aid 50 of branch 30, it can be again livened up almost instantly as needed; operating by induction to the same good effect, as the direct draft of a blacksmith forge. A thing impossible to do where only the natural draft 55 of a short and cold smoke pipe is to be depended on; and almost as difficult if a blower is put in below the fire. Which latter process usually causes smoke and gas to trail through the car, making it necessary 60 to open doors and windows to "air"; thereby losing the benefit of what little heat, thus far has been accumulated in the car.

My device obviates the trouble and delay in the matter of prompt and efficient ventilating and heating a car; and besides being 65

more efficient, is less expensive to install and operate than any other system in use considering all its advantages. Sufficient pure warm air under mild pressure may always be forced into the car as needed, like water 70 is forced against pressure into a steam tight locomotive boiler. Hence it will not be usually necessary to have any windows open; because the car itself is not airtight and will furnish ample exits for the bad air through 75 the cracks and crevices around windows and doors or through small exits T preferably near or under the bottoms of car doors or in the floor where of course no cold air can easily enter against the inside air pressure 80 from pipe 10. Hence there will always be great conservation and control of heat and abundance of fresh warm air for breathing purposes. Even in summer, the windows may all be nailed up, to shut out noise and 85 street dust, and a fine breeze played through the car over the heads of passengers, and out through the back door, left open for the purpose; simply by opening the damper 20 full width (lowered as shown in solid lines) 90 and running the rotary fan which always aids the operation of the acoustic features of this device; as sound travels best with, especially warm, or rarefied, air; and always easier with the wind than against it. The 95 same car will do for winter and summer; so it won't be necessary to buy additional rolling stock of a different type for the changes in the seasons as is usually done.

In the matter of construction: Pipe 10 100 and the conjunctive casing or branch pipe Y, and branch pipes 30 (and its sections 31, 32, and 33) and 24 may be of relatively different lengths than is illustrated; and be so adjusted to each other, as all will work together in harmony in cold weather or separately, as needed at other times; each part aiding the other, in the performance of its respective functions; the action of each modifying the action of the other in the 110 manner and for the purposes set forth.

The outside portions of the combined pipes 10 and warm air casing pipe Y, exposed to the cold and ice, had preferably be jacketed, not illustrated, between the 115 right hand side K and place of intersection with the transom window J'. The jacketing however would not be necessary if all pipes were inside the car under the roof F which arrangement is also within the contemplation of this invention. Also the roof may form one side, of the pipe, upper, or, lower as illustrated; or the pipe may have all its sides completed in the ordinary and usual way.

Should the cold air, receiving, branch 10 get clogged, with snow or ice, it can be readily cleared in a few minutes, by closing the joint outlet 12, with a curtain, not illustrated, or other means; which will force 120

back the warm air around the junction G and thaw out everything in its, temporary outward, passage, through intake 18.

What I claim is:—

- 5 1. The combination, with a car, of a substantially horizontal ventilating pipe communicating rearwardly, with the interior of the car and forwardly with a fresh air intake; a smoke pipe leading to the outer air, from the combustion chamber of a stove placed in the car; a branch of the said air pipe, communicating with the same air intake and with the smoke pipe; means in said branch to regulate the supply of air there-through; power driven means to force the passage of fresh air through the main pipe into the car and also through its branch, when open, into the smoke pipe; means to control the amount of air going into the car, and when needed, to divert the air, so as to enter the branch; whereby, the proper amount of air may be forced, under control, and deflected, at will, from the fresh air pipe into the smoke pipe, so as to compel an upward draft through the smoke pipe and fire of the stove; while the other discharge end of the pipe may serve to ventilate the car.
- 10 2. The combination with a car, of a combination pipe, having two receiving branches and two discharging branches; one receiving branch having an air intake and the other receiving branch having a mouthpiece, both communicating with the pipe and car, inside; one of the discharging branches opening into the car; and the other discharging branch opening into the smoke pipe, of a stove, placed in the car; means to regulate and control the passage of air through the respective branches; whereby the pipe and its respective branches may serve to transmit sound into the car; and likewise serve to ventilate the car; and also force a draft into the smoke pipe so as to stimulate the fire in the combustion chamber of the stove.

- 15 3. The combination with a car, of a combination pipe having three receiving and two discharging branches; one of which receiving branches is in the nature of a pipe and casing around a stove, and portion of smoke pipe therefrom, placed in the car; the second receiving branch communicating with the outer air through an air intake; and the third receiving branch having a mouthpiece; one of the discharging branches opening into the car; and the other discharging branch opening into the smoke pipe of the stove; means to regulate and control the passage of air through the pipe and its respective air receiving branches for the purposes for which they are intended; whereby the pipe and its respective branches, may serve to transmit sound into the car and likewise ventilate the car with air of

milder temperature; and also force a draft into the smoke pipe, so as to stimulate the fire in the combustion chamber of the stove.

4. The combination with a car of a combination pipe discharging into the car; the pipe having three receiving branches comprising respectively a cold air branch having an intake; an acoustic branch having a mouthpiece; and a warm air casing branch, having an inlet, enveloping a heat generating device placed in the car; and means to regulate and control the passage of air through the pipe and its branches for the purposes intended; whereby the pipe may serve to transmit signals into, and also serve to ventilate, the car.

5. The combination with a car of a heating stove therein, having a smoke pipe leading to the outer air; a movable hood capping the smoke pipe, having means to raise it clear out of the way of the upward current of smoke accelerated by the forced draft from the air jet; a horizontal ventilating pipe communicating rearwardly with the interior of the car and forwardly with a fresh air intake; a branch pipe communicating at one end with the ventilating pipe and with the air jet, inside the smoke pipe, at its other end; means to regulate the passage of air through the branch; power driven means to force the air through the ventilating pipe into the car and its branch into the smoke pipe; and means to control the passage of air into the car and to deflect it into the smoke pipe; whereby the main pipe may serve to ventilate the car and its smoke pipe branch co-acting with the smoke pipe hood working in the way described will stimulate the fire in the stove.

6. The combination with a car of a combined transmitting pipe, of the character described, having some portion of the car, for example the roof portion, to serve as one of the sides of the pipe; means to regulate and control the passage of air, sound, and heat through the pipe; whereby the pipe may serve to ventilate the car with freshened warm air and transmit vocal signals into the car.

7. The combination with a car of a combined cold and warm air pipe discharging into the car, and into the smoke pipe by its branch; which pipe is again bifurcated; so as to have one of its receiving branches communicate with the cool fresh outer air; and means to control the passage of air through said branch; the other receiving branch being made in the form of a warm air casing pipe enveloping a stove, and portion of its smoke pipe communicating with the combustion chamber thereof; radiator fins placed at intervals on said smoke pipe inside the casing pipe; means to control the passage of air into the casing pipe branch; means of extending the casing pipe;

- ceiving branch, along the floor to any portion of the car; so that cold air coming into the fresh air intake is mingled with the warm air coming out of the casing; the air, 5 drawn from near the floor and, going through the casing being sufficiently warmed by the stove, smoke pipe and, the radiator fins acting as baffles to prevent too rapid passage of air through the casing.
- 10 8. The combination with a car, of a combined acoustic, ventilating, and heating pipe having three receiving branches; one branch to convey the outer fresh air into the pipe, the second branch to convey the 15 warmer inner air into the pipe; and the third branch to convey sounds and signals into the same pipe, which branch may have a telescopic extension mouthpiece; which pipe also has a plurality of discharging 20 branches; one of which conveys cold air from the pipe into the smoke pipe communicating with a stove placed in the car, to produce a forced draft to stimulate the fire in the stove; the remaining branch and 25 branches co-acting, to jointly convey the air, modified by heat, and also the sounds and signals, into the car; means to control the passage of air through the pipe and its air conveying branches for the purposes described.
9. The combination with a car of a combination pipe and its branches; a smoke pipe communicating with the combustion chamber of a stove in a casing pipe, enclosing, 30 the heating apparatus, usually a stove and smoke pipe, and forming a branch of the combination pipe; which latter has another branch to receive fresh air; and again another discharging branch by which
- the air may be diverted into the smoke pipe 40 to stimulate the fire of the stove; and lastly a receiving branch terminating in a mouthpiece into which the names of streets and stations may be called; and means to force, divert and otherwise control the passage of 45 air through the pipe and its air conveying branches; so that the apparatus as a whole, and its respective parts in conjunction therewith, separately, may be used, as respectively needed, to ventilate the car, force the 50 fire, and act as street annunciator.
10. The combination with a car of a bifurcated ventilating and heating pipe; its discharge end opening into the car; one of its branches receives fresh cool air from 55 outside the car; the other branch, enveloping a heating apparatus, to receive warmed air taken from any desired part inside the car; both of which branches are joined to the combined pipe opening overhead into the car; the extension of the warm air branch consisting of a longitudinal pipe in the vicinity of the floor and communicating with the interior of the car, and also with the warm air casing receiving branch, 60 of the bifurcated pipe; its purpose being to draw the colder air from the floor into the warm air receiving branch of the bifurcated pipe; and means to regulate and control the 65 passage of air through the pipe and any 70 of its air conveying branches.

In testimony whereof, I sign this specification in the presence of two witnesses.

LE VERT CLARK.
